UNITED STATES PATENT OFFICE.

HENRY ADLER, OF ALLEGHENY, PENNSYLVANIA.

DESIGN FOR A GAS-STOVE.

SPECIFICATION forming part of Design No. 28,497, dated April 19, 1898.

Application filed June 19, 1897. Serial No. 641,519. Term of patent 14 years.

To all whom it may concern:

Be it known that I, HENRY ADLER, a citizen of the United States, residing at Allegheny in the county of Allegheny and State of Pennsylvania, have invented a new and original Design for Gas-Stoves, of which the following is a specification, reference being had therein to the accompanying drawing, in which the figure illustrates a perspective view of a gas-stove embodying my design.

The leading features of my design consist in a gas-stove having the shape and form, as well as the configuration and ornaments, substantially as herein shown and described.

As shown in the drawing, *a* represents the front base-plate, which is formed in a curve *b* and is provided with a seat *c* in the top thereof for the reception of the fender *d*, which rests against the burner *e* and is provided with the handle *f* thereon. The back *g* and sides *h* are formed from one piece of metal and bent

to shape, so as to form the front panels *i*, which are ornamented, as shown.

In the rear of the burner *e* is a plate having vertical corrugations and provided with 25 perforations therein, and in front of the plate are branches *k*.

The top plate *m* fits over the back *g* and sides *h* and is formed on a curve and provided with a series of openings or perforations *n* 30 therein. A downwardly-projecting flange *o* is formed on the top plate *m*, which extends down over the panels *i* and is curved at its lower end *o'*. The top plate *m* and flange *o* are ornamented, as shown.

35

What I claim as my invention is—

The design for a gas-stove, substantially as herein shown and described.

HENRY ADLER.
